UNITED STATES PATENT OFFICE.

EDMUND H. STROUD, OF CHICAGO, ILLINOIS.

APPARATUS FOR SUPPLYING POWDERED FUEL TO FURNACES.

1,353,291.

Specification of Letters Patent. Patented Sept. 21, 1920.

Application filed February 26, 1917. Serial No. 150,911.

To all whom it may concern:

Be it known that I, EDMUND H. STROUD, a citizen of the United States, and a resident of Chicago, county of Cook, and State of Illinois, have invented certain new and useful Improvements in Apparatus for Supplying Powdered Fuel to Furnaces, of which I do declare the following to be a full, clear, and exact description, reference being had to the accompanying drawings, forming a part of this specification.

The present invention has relation to apparatus designed for supplying to furnaces for generating steam or other purposes, powdered or finely divided coal or other fuel intimately mixed with air in proper quantity and so controlled as to insure complete combustion, an example of this type of apparatus being set forth in Letters Patent No. 707,992, to G. M. Warner, August 26, 1902.

The object of the present invention is more especially to provide an improved apparatus, of the character stated, for use in connection with the furnaces of locomotive engines, and to this end the invention consists in the features of novelty hereinafter described, illustrated in the accompanying drawings and particularly pointed out in the claims at the end of this specification.

Figure 1 is a view partly in side elevation and partly in vertical section showing a locomotive tender and a portion of a locomotive boiler and furnace to which my invention is applied. Fig. 2 is a view in vertical section on line 2—2 of Fig. 1. Fig. 3 is an enlarged detail view in front elevation, parts being shown in vertical section with the apparatus in place upon the tender of the locomotive. Fig. 4 is a view in vertical section on the line 4—4 of Fig. 3, a portion of the front wall of the boiler furnace being shown in vertical section.

A designates the locomotive boiler and B designates the fire box and furnace thereof, the wall at the firing end of the fire box B being formed with suitable openings b to receive the conical ends or nozzles c of the trunk pipes or conduits C through which the supply of powdered fuel and air will be admitted to the furnace B. The trunk pipes C are preferably formed of flexible armored tubing and are of proper length to extend between the tender D and the furnace B and the inner end of each of the pipes or conduits C is connected to the discharge spout e of

the corresponding fan casing E or E'. Each of the fan casings E and E' will contain vanes or blades E² of suitable construction, such, for example, as shown in Warner Patent No. 707,992 above mentioned. These fan casings E and E' are preferably formed of separate sections bolted together and the base e' of such casing rests upon the floor d of the locomotive tender D. In the preferred form of my invention, the vanes or blades E² of the fan casings E and E' are mounted upon a shaft or shafts in axial alignment driven from an appropriate motor (by which term is meant any suitable motive power unit), an electric motor F being indicated in the drawings, this motor being shown as part of the device and located centrally between the fan casings E and E'. The casing F' of the motor F is suitably connected to and sustained by the fan casings E and E' and this casing F' of the motor is provided upon its interior with suitable bearings for the motor shaft that constitutes also, preferably, the shaft of the vanes or blades within the fan casings E and E'. Each of the fan casings E and E' has a laterally extending central annular rim or flange E³ over the outer end of which extends a series of plates e³, e⁴ and e⁵ (preferably three in number) forming an air admission valve, that are formed with air admission ports. Through the central openings of these plates e³, e⁴ and e⁵ passes a flanged sleeve or eyelet e⁶ the interior diameter of which is slightly larger than that of the shaft which the sleeve or eyelet encircles. The plates e⁴ and e⁵ are provided each with a handle e⁷ (see Fig. 4) whereby the plates may be turned so as to increase or diminish the supply of air admitted to the fan casing. As shown, the plates e³, e⁴ and e⁵ are held against the outer face of the annular flange E³ by means of two or more clamp dogs e⁸, (see Fig. 3) the hooked ends of which bear against the outer face of the plate e⁵. The clamps e⁸ are shown as mounted at the side of a yoke-shaped frame G that is secured to the annular rim E³ of the corresponding fan casing by means of suitable angle plates e¹⁰ and the outer end of the yoke-shaped frame G is formed with a bearing to receive the outer end of the shaft g of the fans and motor. This bearing may consist of a casting or forging g² having a central sleeve from which projects the

arms g^4 that are bolted to the frame G. From the outer portion of the frame G at its front is bolted a bracket G' the inner end of which is secured to the flange E³ of the fan casing.

Upon that part of the shaft g within the yoke-shaped frame G is slidably mounted a worm sleeve H that is driven from the shaft g and one end of this worm sleeve H is provided with an annular groove to receive studs or trunnions projecting from the upper yoke-shaped end of a shifting lever J that is pivotally mounted, as at j , in the yoke-shaped frame G. The lower end of the shifting lever J is provided with a pivoted, hand-actuated dog j^2 adapted to engage with a sector plate j^3 that is secured to the yoke-shaped frame G so that when the shifting lever J is operated to shift the worm sleeve H, this lever and the worm sleeve can be held in the desired position. Other means can be employed for this purpose. The worm sleeve H engages a worm gear K that is mounted upon the inner end of a counter-shaft k that passes through a bearing sleeve or housing K', the chambered flange portion k^2 of which (containing the worm wheel K) is bolted to the yoke-shaped frame G. Upon its outer end the counter-shaft k has keyed thereto a sprocket wheel M, around which passes a sprocket chain M' that passes around a sprocket wheel M² on the outer end of a conveyer shaft N (see Fig. 4).

Each conveyer shaft N has mounted thereon a screw conveyer N' that extends within a conveyer tube N². In the lower part of the outer end of each conveyer tube N² is formed an opening n with a depending annular flange n' that is connected to a pipe O that leads downwardly to the top of the flange E³ of the adjacent fan casing in order to deliver powdered fuel into the eye of the fan casing and into the path of the current of air as it is drawn inward by the vanes or blades of the fan casing through the air admission ports.

The inner end of each of the conveyer tubes N² is provided at its top with an elongated opening and is placed within a pocket p that is formed at the bottom of the coal bin P on the locomotive tender D.

As shown, the coal bin P of the tender D is placed above and extends downwardly into the upper part of the water tank D' of the tender D, the front of this water tank D' terminating at a sufficient distance from the front of the tender D to afford a compartment D² to receive the fan casings and motor.

The bottom of the coal bin P is preferably formed with inclined bottom walls p' and p^2 as shown in Fig. 2 and with an inclined front wall p^3 to better direct the powdered coal to the openings in the conveyer tubes

N², and the top of the coal bin will be furnished with suitable openings through which fuel may be supplied to the bin, these openings being closed by hinged covers.

From the foregoing description it will be seen that when powdered fuel is to be delivered to the fire box or furnace of a locomotive, revolution will be imparted to the blades of the fan from the motor F after which the fireman by means of the shifting lever J will throw the worm sleeves H (one or both) into engagement with the worm wheels K so as to cause the conveyers N' to feed the powdered fuel from the coal bin P through the conveyer tubes N² and pipes O to the central openings of the fan casings E and E'. By adjusting the valve plates e^4 and e^5 the fireman can regulate with exactness the amount of air necessary to be admixed with the supply of powdered fuel in order to effect a most thorough and perfect combustion thereof within the firebox of the locomotive. The powdered coal, or other fuel, with all the air necessary for combustion, is conducted by the conduits C to the firebox of the locomotive and passes therein through the openings b at the usual firing end of the firebox, where the mixture meets either a small preliminary flame or incandescent brick work, and the two elements of the fuel being so thoroughly mixed and in such correct proportions, the mixture ignites almost instantly insuring thereby most thorough and effective and rapid combustion.

In the event that a change of adjustment is needed to secure said very perfect combustion, it can be made by means of the air valve or throttle at the eye of each fan on one side of each fan casing by which the entire supply of air to be used is admitted to the firebox of the locomotive and can be accurately regulated by the fireman, who is able to observe the combustion within the fire box or furnace B through a peep-hole b^2 at the firing end thereof. And thereafter the speed of operating the stoking and mixing and burning device governs the quantity of fuel burned, and the temperature in the firebox, the quantity of steam made and the rapidity of making it, and the control of the motor or steam turbine or other motive power unit (which is built into and which is a part of said stoking, mixing and burning device), will be effected by a suitable electric controller, steam throttle or other suitable means (not shown) within the cab of the locomotive or upon the front end of the tender.

By providing the tender of the locomotive with a bin for the powdered fuel arranged above the forward portion of the water tank, and by inclining the walls of the bin P as shown, powdered fuel can be readily de-

livered into the open inner portions of the conveyer tubes so that the conveyers will serve to effectively feed the fuel from the bin until the supply of fuel is exhausted.

5 So, also, by providing a compartment D² at the front of the tender, a protected space is afforded to receive the fan casings and motor in a convenient and accessible location.

10 By having two conduits for conducting the fuel from the tender to the firebox of the locomotive and by providing two fan casings and conveyers for delivering powdered fuel thereto and by the arrangement of the 15 motor or turbine between the fan casings, I am enabled to provide an extremely simple and compact arrangement which will most effectively deliver the fuel to the firebox and which will insure that the fuel shall be 20 properly supplied; and if any choking within either of the fan casings or the conduit leading therefrom occurs, the other fan casing will continue to supply a requisite amount of fuel until the obstruction has 25 been removed. By my improved apparatus not only is smoke not made and a great saving of fuel and water effected, but there can be little or no back pressure in the cylinders of the locomotive, because there is practically no need to exhaust the steam through the smoke stack to create a draft since all 30 the air requisite for the burning of the fuel is supplied through the fan casings. Moreover, the fireman is able to instantly check, 35 increase or diminish the fire within the firebox as the conditions of the train load, the speed required and the nature of the grades may demand. Other advantages incident to my invention will be readily understood 40 to those familiar with this class of apparatus.

While I have described what I regard as a preferred embodiment of my invention, I wish it understood that the details above 45 set out may be varied without departing from the spirit of the invention and the features of the invention may be employed without its adoption as an entirety.

While the preferred practice of my invention is above described, it will be readily understood that the engineer or fireman of the locomotive may prefer, in the operation of the device, to use more or less draft created by exhausting the steam through the 55 smokestack of the locomotive, in addition to the forced draft created in my improved apparatus.

Having thus described my invention, what I claim as new and desire to secure by 60 Letters Patent is—

1. An apparatus of the character described, comprising a receptacle for powdered fuel, a plurality of conveyers for leading the powdered fuel from said receptacle, 65 a pair of fans, a motor arranged between

and in axial alinement with said fans for imparting revolution thereto, a common shaft for said motor and said fans, connections for delivering the powdered fuel from said conveyers to the casings of said fans, 70 and valve mechanism for delivering air in regulated quantity to said fan casings.

2. An apparatus of the character described, comprising a receptacle for powdered fuel, two conveyers for leading the 75 powdered fuel forwardly from said receptacle, two fans located below the forward ends of said conveyers, a motor arranged between and in axial alinement with said fans and having its casing connected to the 80 casings of said fans, connections for delivering the powdered fuel from said conveyers to said fans, valve mechanism for delivering air in regulated quantity to said fans, and discharge conduits leading forwardly from the peripheries of the casings 85 of said fans.

3. An apparatus of the character described, comprising an elevated bin for powdered fuel having its bottom formed 90 with walls downwardly and outwardly inclined from the center, pockets at the bottom of said bin near the sides thereof, substantially horizontal conveyer tubes located in said pockets and extending forwardly 95 therefrom, conveyers arranged within said conveyer tubes, fans arranged below the forward ends of said conveyer tubes and having forwardly directed discharge conduits, a pipe leading downwardly from the forward 100 end of each conveyer tube to a central opening of the subjacent fan casing, valve mechanism for admitting air in regulated quantity to the central opening of each fan casing below the point of delivery of the powdered 105 fuel thereto, suitable gear mechanism connecting the shaft that extends through each fan casing with the forward end of the adjacent conveyer, and means for throwing said gear mechanism into and out of action. 110

4. An apparatus of the character described, comprising an elevated bin for powdered fuel having its bottom formed with walls downwardly and outwardly inclined from the center, pockets at the bottom of said bin near the sides thereof, substantially horizontal conveyer tubes located in said pockets and extending forwardly 115 therefrom, conveyers arranged within said conveyer tubes, fans arranged below the forward ends of said conveyer tubes and each 120 fan having a central opening on one side of the casing and a discharge conduit extending forwardly from the lower portion of the fan casing, a pipe leading 125 downwardly from the forward end of each conveyer tube to the central opening of the adjacent fan casing valve mechanism for admitting air in regulated quantity to the central opening of each fan casing below 130

- the point of delivery of the powdered fuel thereto, suitable gear mechanism connecting the shaft that extends through each fan casting with the forward end of the subjacent 5 conveyer, and a motor arranged between said fan casings and whereby both of said fans are driven, and means whereby the gear mechanism adjacent each of said fans may be thrown into and out of action.
- 10 5. The combination with a locomotive fire box, of a tender having a water tank, an elevated bin for powdered fuel and a compartment in front of said tank and bin, a conveyer extending forwardly from said bin 15 into said compartment, a fan located in said compartment of the tender and below the front end of said conveyer, a motor also located in said compartment for driving the fan, a pipe for powdered fuel leading downwardly from said conveyer to said fan, valve mechanism for admitting air in regulated quantity to said fan, and a closed conduit 20 quantity to said fan, and a closed conduit

leading forwardly from the periphery of said fan to said locomotive fire box.

6. The combination with a locomotive fire 25 box, of a tender having a water tank, an elevated bin for powdered fuel and a compartment in front of said tank and bin, a plurality of substantially horizontal conveyers extending forwardly from said bin, 30 fans located in said compartment of the tender and below the forward ends of said conveyers, a motor located in said compartment between said fans and in axial line thereof, a common shaft for said motor and 35 said fans, a pipe for powdered fuel leading downward from each of said conveyers to the subjacent fan, valve mechanism for admitting air in regulated quantity to each of said fans, and a closed conduit leading forwardly from the lower portion of each of the casings of said fans to said locomotive fire box.

EDMUND H. STROUD.
